(No Model.)

J. ANDRÉ.

AUTOGRAPHIC TELEGRAPH.

No. 251,684.

Patented Dec. 27, 1881.

UNITED STATES PATENT OFFICE.

JACQUES ANDRÉ, OF PARIS, FRANCE.

AUTOGRAPHIC TELEGRAPH.

SPECIFICATION forming part of Letters Patent No. 251,684, dated December 27, 1881.

Application filed January 11, 1881. (No model.) Patented in France November 6, 1880, and December 13, 1880, in Belgium December 14, 1880, and in Austria-Hungary March 25, 1881.

To all whom it may concern:

Be it known that I, JACQUES ANDRÉ, of Paris, in the Republic of France, have invented a certain Improvement in Means for the 5 Transmission of Electric Currents, of which the following is a specification, reference being had to the accompanying drawings.

This invention is capable of numerous practical applications, among which I will mention 10 particularly electric telegraphy; but it is also applicable in all the conditions in which it will operate to reproduce instantaneously, at any distance upon paper or other material, written texts, signs, drawings, musical notations, or any 15 outlines. These reproductions may be made of equal dimensions, reduced or enlarged.

In carrying out my invention I employ a band, of any width and length, of a mixed tissue or woven fabric the warp of which consists of 20 any number of metallic conducting-wires, insulated electrically from one another by means of a weft of fibrous material. Such a band has before been used, and I do not therefore claim it as of my invention. The electrical insulation 25 of this tissue conductor is completed by a coating of suitable material, depending on the nature of the applications which are made of the invention.

The number, the thickness, and the spacing 30 of the wires of the tissue conductor should vary naturally, according to the results to be obtained and the dimensions of the surface which it is wished to reproduce.

For electric telegraphy at great distances I 35 employ in the composition of the tissue conductor wires of which the aggregate presents a sufficient section not to offer too great a resistance to the passage of the current. When it is necessary to make use of a great number 40 of wires a tissue might be required of a width so considerable as to present several practical inconveniences. To obviate these I arrange the tissue in bands of appropriate width, which I superpose in suitable number.

45 In the accompanying drawings, Figure 1 represents a vertical section of a machine or apparatus embodying my invention, and Fig. 2 represents a plan of a commutator which receives the ends of two sections of the tissue 50 or band conductors at an intermediate station in the line.

Similar letters of reference designate corresponding parts in both figures.

The band of conducting-tissue extends from one extremity of the line to the other. It is cut at 55 each intermediate station in such manner that the sections or portions A B communicate respectively with the neighboring stations, as will presently be seen. The extremities of the wires of the tissue conductor are to be connected 60 with transmission-rubbers, composed of a tissue like that of the conductors, but preferably made with finer wires, of which each corresponds with a wire of the tissue conductor. This connection is not, however, made directly, 65 but through the medium of a commutator, which may be a kind of comb, as hereinafter described, and to which the said rubbers are attached.

To give stiffness to the tissue forming the 70 rubbers, it may be coated with an insulating substance, such as wax.

As I have just mentioned, the rubbers are attached to the commutator, and against this the ends of the sections of the tissue conductor 75 are arranged to abut. This commutator of comb-like form is made of a plate of non-conducting material having a number of slits, which produce as many divisions or teeth as there are wires in the tissue conductor. It results from this arrangement that in each division or tooth of the comb there are two wires, one in front of the other, belonging to two neighboring sections, A B, of the tissue conductor, and communicating respectively with 85 the two neighboring posts of the intermediate station. It will be seen, then, that it is sufficient to bring together and put in contact the wires of the two portions of the line to establish what is known in telegraphy as the "direct communication"—that is to say, to put in direct 90 communication the two parts in question without the dispatches being stopped at the intermediate station.

The comb may be placed, as represented in 95 the accompanying drawings, upon a table, a, and to facilitate the operations which I am about to describe the extremities b c of the sections A B of the tissue conductor, which abut against the comb d, are taken each between 100 two small boards, e f or g h, which hold them.

The boards e f and g h may be moved toward

and from each other by means of screws *a'*, as seen in Fig. 1. By bringing these boards together the contact is established between the wires; on the contrary by separating them the extremities of each of the wires are put in contact with a metallic clasp or contact-piece, *i j*, with which the bottom of the slit of the comb is furnished, and to which is attached one of the wires of the tissue which constitutes the rubber. The extremities of each rubber *k* are taken between two insulating-plates, *l l*, of glass, for example, held by any suitable means, and allowing the protrusion of the ends of the wires beyond them to a sufficient length to leave them the desired flexibility—about one centimeter. These plates *l l* are carried by a support, *m*, which permits them to have given to them the desired inclination and regulate the pressure with which they impinge the surface of contact *n*. The transmission is made directly by the extremities of the rubber *k* without the aid of any intermediate device, as will be presently explained. For this purpose there may be used an original prepared by any of the means now in use for electro-autography. In other words, I can reproduce by my invention any original constituted by any surface whatever presenting alternations of conductibility and of non-conductibility—for example, typographic characters, perforated paper, &c. I can also use the ordinary method of removing from a metal plate portions of a coating of insulating matter with which the surface of the plate has been covered. I however prefer to write or trace on a clean metal plate with a pen charged with colored resinous ink, with a colored alcohol varnish, or with any other convenient protecting material, and afterward to oxidize the said plate by any suitable reagent—for example, if it be of zinc, by means of nitro-sulphate of copper. I then dissolve away the ink by means of any suitable solvent, (soda in case of alcoholic or resinous varnish, &c.,) and the metal is then found bright over the whole extent of the writing or tracing. The width of the original is preferably the same as that of the rubber *k*. To transmit this original it is made to pass under the extremities of the rubber *k* at the transmitting-station. At the same time there is caused to pass under the rubber of the receiving-station a receiving-surface consisting of sheets or a band of paper or cloth, or other material coated with a suitable matter decomposable by the action of electricity, upon which the original is exactly reproduced by the action of the electric currents. I prefer to use for the telegraphic reception continuous bands *o*, prepared with a suitable chemical, passing over a metallic cylinder, *n*, ordinarily of iron, having imparted to it a rotary motion, of which the speed may be regulated by a rotary flier formed by a disk, *p*, capable of a variable inclination. This disk, articulated upon a vertical arbor, *q*, which, with the cylinder *n*, is driven by any clock-motion, has attached to its periphery one end of

a rod, *r*, of which the other end is attached to a screw, *S*, which is adjustable longitudinally. This rod *r* may turn freely on the screw; and it will be understood that by raising or lowering the screw the disk is more or less inclined relatively to its axis. The air exercises then a variable pressure upon the surface of the disk, and consequently its movement is regulated, two counterpoises, *t*, giving stability to the flier. 70

Motion is imparted to the cylinder *n* by an ordinary train of clock-work, which is not here represented, as it forms no part of my invention, and the clock-work transmits motion to the vertical arbor *q* of the flier through a wheel, *x*, which engages with a worm or screw on said arbor, as clearly seen. 80

One of the poles of the battery *T* is in communication with the ground, while the other communicates by a wire, *u*, with the receiving-cylinder *n*. The communication with the line is made by the rubber *k*, then by one of the sections of the tissue conductor *A* or *B*, according as the dispatches are received from one side or the other. The figure or tracing being always made by the positive pole, it will be seen that I can receive either under or above the band *o* by inverting the poles. In the first case the points of the rubber *k* trace directly. 90 In the second case the tracing or figure is made by the metal of the cylinder *n*, on which is applied the receiving-band *o*. The current, passing then from the metal *n* to the points of the rubber *k*, diffuses itself sufficiently and according to the thickness of the receiving-band *o*. This second disposition is preferable, and the cylinder should be kept dry and clean. For this purpose it works against two pads, *v*, of wick, very slightly greased and held by spring supports, to which are applied screws to produce a regulated pressure. Moreover, under the cylinder is a vessel, *w*, containing materials necessary for producing a permanent disengagement of hydrogen. 100 110

The moistening of the receiving-band *o* may be made either by preliminary soaking or by a special moistening operation during the reception. 115

What I claim as my invention is—

The combination, in an electro-autographic telegraph apparatus, of the two bands *A B*, of fabric the warp of which is composed of conducting-wires, the slotted or comb-like commutator-body which receives the ends of said conducting-wires, the contact-pieces secured in the slots of said commutator-body, the rubbers *k*, comprising wires connected with the several contact-pieces, and the rotating cylinder *n*, substantially as specified. 120 125

This specification signed this 11th day of December, 1880.

JACQUES ANDRÉ.
